US00D465027S

(12) **United States Design Patent** (10) Patent No.: **US D465,027 S**
Huffman (45) Date of Patent: **** Oct. 29, 2002**

(54) **DENTAL MODEL BASE HAVING A SINGLE ROW OF APERTURES**

(75) Inventor: **Ronald E. Huffman**, Oro Valley, AZ (US)

(73) Assignee: **Ronald Huffman**, Oro Valley, AZ (US)

(**) Term: **14 Years**

(21) Appl. No.: **29/148,947**

(22) Filed: **Sep. 28, 2001**

(57) **CLAIM**

The ornamental design for dental model base having a single row of apertures, as shown and described.

DESCRIPTION

FIG. 1 is a perspective view of the present invention.

FIG. 2 is a top plan view thereof.

FIG. 3 is a bottom plan view thereof.

FIG. 4 is a side view thereof.

FIG. 5 is a front elevation view thereof; and,

FIG. 6 is a rear elevation view thereof.
